ELECTRIC COUPLING SYSTEM

Carl E. Trube, Maplewood, N. J., assignor to
Hazelton Corporation, Jersey City, N. J., a corporation of Delaware

Application July 2, 1926, Serial No. 120,045
Renewed June 18, 1930

38 Claims. (Cl. 179—171)

This invention relates to electric coupling systems particularly adapted for use with radio-frequency vacuum tube amplifiers and more particularly to circuit arrangements which operate most effectively over a relatively wide range in frequency. This application is a continuation-in-part of my copending application Serial No. 101,906, filed April 14, 1926. In United States Letters Patent No. 1,762,431, granted June 10, 1930, are shown electric coupling systems arranged to give effective operation over a range in frequency by providing a single manual device to adjust simultaneously the tuning and the voltage ratio. The present invention constitutes an improvement over that of the above-mentioned Patent No. 1,762,431 in that the coupling system is so arranged as to give a voltage ratio that varies automatically with the frequency, thus leaving only the single adjustment of tuning for different frequencies. This simplifies the construction and increases the reliability of the system.

This invention is applicable both to coupling systems interposed between consecutive vacuum tubes of an amplifier, and to the coupling system interposed between an antenna and a vacuum tube. Furthermore, this invention is applicable to vacuum-tube amplifiers that are stabilized by the use of a high step-up voltage ratio in the coupling system, as described in my prior patent above referred to, to amplifiers that are stabilized by partial neutralization or by other means, and to amplifiers wherein complete neutralization of capacity coupling is attained and wherein regeneration is eliminated.

The degree of responsiveness or amplification of an inter-tube coupling system is dependent, among other factors, on the voltage ratio of the system and the nature and magnitude of the input impedance of the system, which comprises the plate circuit load impedance of the preceding vacuum tube. Ordinarily, the input impedance of such a system varies substantially over the tuning range of the system, following generally the impedance variations of the secondary tuned circuit, increasing with frequency when the secondary circuit is tuned by means of a variable condenser and decreasing with frequency when the secondary circuit is tuned by means of a variometer. As a result of this impedance variation, at each frequency there is a particular ratio of output voltage to input voltage that will give the best compromise design. This ratio generally varies rapidly with the frequency, being relatively high at high frequencies. Similarly, in the antenna circuit, there is a voltage ratio that gives

the best compromise design, considering sensitivity and selectivity and this ratio also generally varies rapidly with frequency. This invention provides means for securing substantially the most desirable ratio at all frequencies in order to procure the most desirable frequency-response and selectivity characteristics without having any adjustable element except the tuning adjustment.

Stated in another way, the present invention provides a new and improved means for procuring an effective coupling between the input and output circuits of the coupling system that varies with frequency in a preselected manner under the control of the designer. By the term "effective coupling" is meant the ratio of the effect coupled into the secondary or output circuit, which may be a current or a voltage, to the input or primary effect, which may also be either a current or a voltage. When the effective coupling is measured as the ratio of the voltage coupled into the output circuit to the input current, as is the case in an inter-tube coupling system, this ratio may be termed the "effective mutual reactance" of the coupling system.

A feature of the invention is the maintenance, during tuning, of the effective reactance appearing at the output of the vacuum tube within such limits that the reaction upon the input circuit through the inherent interelectrode capacity of the tube is held within predetermined limits and in any event is insufficient to produce oscillations.

Referring to the drawings:

Fig. 1 illustrates a vacuum tube and an electric coupling system of the conventional type, in which the voltage ratio does not vary with the frequency. Fig. 1A is the response-frequency curve corresponding to Fig. 1.

Fig. 2 illustrates a modification of Fig. 1 and also is a conventional type. Fig. 2A gives response-frequency curves corresponding to Fig. 2 or to Fig. 6.

Fig. 3 illustrates an electric coupling system in which the voltage ratio varies with the frequency in accordance with this invention, but in which the variation with frequency is more rapid than is usually desired. Fig. 3A is the corresponding response-frequency curve.

Fig. 4 illustrates a preferred form of this invention which combines Figs. 1 and 3 to give a voltage ratio which varies with the frequency in a desired manner. Fig. 4A is the response-frequency curve corresponding to Fig. 4 or to Fig. 5.

Fig. 5 is the combination of Figs. 2 and 3 and gives results similar to those of Fig. 4.

Fig. 6 illustrates an alternative arrangement in which some of the advantages of this invention may be secured.

Fig. 7 also illustrates a modification of this invention in which some of the advantages may be secured. Fig. 7A is the corresponding response-frequency curve.

Fig. 8 is a further modification, in which the primary circuit is isolated from the secondary and main resonant circuit.

Fig. 9 illustrates the application of this invention to a complete uni-control radio-frequency amplifier, including the coupling between the antenna and a vacuum tube.

For convenience, the voltage E_2 measured at the output terminals of the coupling system may be called the "output voltage", and the voltage E_1 measured at the input terminals of the coupling system may be called the "accompanying alternating voltage" or "input alternating voltage". It may here be pointed out that the output voltage will in certain modifications of this invention be identical with the "resonant voltage", i. e., the voltage across the adjustable main resonant circuit, as in Figs. 3 and 6; while in other modifications the output voltage will not necessarily be the same as the resonant voltage, as in Fig. 5.

In the coupling system of Fig. 1, the ratio of the output voltage E_2 built up across the resonant circuit C_2 , L_2 to the accompanying alternating input voltage E_1 across the coil L_1 is substantially equal to the ratio of the self-inductance L_2 to the mutual inductance M , and is therefore independent of the frequency. The rate at which the reactances and the resistances vary with the frequency, however, is such that the input impedance at resonance as measured between the terminals of L_1 is relatively low at low frequencies. Therefore, both the effective coupling and the response or amplification are correspondingly low. For reasons of selectivity and stability, it is ordinarily the practice to make the voltage ratio (E_2/E_1) higher than that giving maximum amplification at the highest frequency. This is especially necessary in an unneutralized amplifier, where stability is particularly difficult to attain at high frequencies. The result is that both the effective coupling and the amplification fall off markedly at the lower frequencies, as illustrated by the full-line curve in Fig. 1A, which indicates qualitatively the relative response of a complete amplifier as a function of frequency. In a neutralized amplifier it is possible to lower the voltage ratio, by employing larger values of self-inductance L_1 and thus of mutual inductance M , resulting in a response curve such as the dotted line in Fig. 1A; but still the amplification falls off at the lower end of the frequency range, and furthermore the selectivity is impaired at the higher frequencies.

In place of the series-feed arrangement of Fig. 1, in which direct current is supplied by the battery B connected in series with the primary coil L_1 , it is sometimes the practice to employ a parallel-feed system as illustrated in Fig. 2, where the direct plate current is supplied through the choke coil L_3 which is effectively in parallel with the input circuit of the coupling system, including condenser C_5 and coil L_1 . It is the practice to design the choke coil L_3 and the blocking condenser C_5 so that L_3 offers a very high impedance to radio-frequency current, and

C_5 a very low impedance; the former acting substantially as an open circuit and the latter as a short circuit. Under these conditions, the system of Fig. 2 is electrically equivalent to that of Fig. 1, and has therefore the same disadvantages, giving the same response-frequency curve, as represented by the full-line curve in Fig. 2A.

In the arrangements of the prior art, of which Fig. 1 is typical, the coupling transformer generally has an effective step-up ratio greater than the optimum value; in other words, the primary or input impedance of the coupling system is less than the internal plate resistance of the tube. By virtue of the use of the greater than optimum value instead of the optimum value, the selectivity is greatly improved, while the amplification is decreased by only a small amount. In this region of operation, an increase in the effective step-up ratio causes a further departure from the optimum value and results in decreasing the amplification, and vice versa.

In Fig. 3, there is provided a system essentially the same as that illustrated in Fig. 1 of my patent above referred to, but the condenser C_3 now has a fixed capacity, and the condenser C_4 alone is the adjustable tuning element. This circuit, like Fig. 2, embodies a parallel feed; and it will also be understood that the choke coil L_3 has a very high impedance. The resonant circuit then includes the two condensers C_3 and C_4 and the inductance coil L_2 . As the impedance of L_2 varies directly with the frequency, and the impedance of C_3 varies inversely with the frequency, the ratio E_2/E_1 of the resonant output voltage across L_2 to the accompanying alternating input voltage across C_3 varies as the square of the frequency. Such a variation is in the right sense to result in an improvement over the constant ratio given by the arrangements of Figs. 1 and 2, and under some conditions may be satisfactory, particularly when stability is the most serious limitation and where the high-frequency losses in the coupling system are especially low, but ordinarily such a variation is too rapid in rate, resulting in a rapid falling off of both the effective coupling and the response at the higher frequencies, as shown in Fig. 3A.

In general, therefore, an effective combination of Fig. 1 or 2 with Fig. 3 will give the most desirable variation with frequency of the voltage ratio E_2/E_1 and of the response of the system. The combination of Fig. 1 with Fig. 3 is illustrated in Fig. 4, in which the main resonant circuit comprises the two condensers C_3 and C_4 and the inductance coil L_2 . If, as before, L_2 is a choke-coil of very high impedance, then between the input terminals of the coupling system there are two coupling elements across which are developed two components of voltage: that across the electromagnetic or inductive coupling element L_1 which is constant relative to the resonant output voltage E_2 ; and that across the electrostatic or capacitive coupling element C_3 which varies inversely as the square of the frequency relative to E_2 . Thus, there is obtained a resultant voltage ratio which increases with frequency but at a rate which is somewhat less than proportional to the square of the frequency, a variation of this sort being desirable for certain types of receivers. By properly choosing the magnitudes of the capacity C_3 and the mutual inductance M , it is thus possible to obtain any desired law of variation of both the voltage ratio E_2/E_1 and the effective coupling of the system intermediate between that of Fig. 1

and that of Fig. 3. That is to say, the input voltage relative to the output voltage will fall off as the frequency increases, but the rate of falling off, and thus the frequency-response characteristic of the coupling system, is under the control of the designer and the voltage ratio and response can be given preselected values at any two specified frequencies. Ordinarily, it is preferable to have the voltage across C_3 considerably exceed that across L_1 at the lower radio frequencies, while at the higher radio frequencies the voltage across L_1 may be the greater. More specifically, elements C_3 and L_1 cause the ratio of the output alternating voltage to the input voltage (E_2/E_1) to fall off automatically when the tuning element C is adjusted for higher frequencies, but at a rate which is less rapid than the inverse square of the frequency. Under this condition, the response curve has a form such as illustrated in Fig. 4A.

In the coupling system of Fig. 4, coil L_1 is ordinarily wound with only a few turns, while coil L_2 is wound with many times that number. Capacity C_3 is much larger than capacity C_4 . The actual inductance and capacity values may be of the same order of magnitude as the values given hereinafter for the identically numbered elements of the circuit of Fig. 5.

Fig. 5 illustrates the combination of Fig. 2 with that of Fig. 3, the coupling system, per se, being identical with that of Fig. 4 of my previously mentioned copending application, Serial No. 101,906. The operation is essentially the same as that just described for Fig. 4 and gives a response-frequency curve as in Fig. 4A. The main resonant circuit in this instance comprises the two condensers C_3 and C_4 and the inductance coil L_2 . There is an advantage in the circuit arrangement of Figure 5 over the preceding circuits in that in the circuit of this figure the output voltage is the sum of the resonant voltage; (i. e., the voltage developed across the adjustable main resonant circuit C_4 , C_3 , L_2) and the voltage across inductance L_1 . Ordinarily L_3 is a choke-coil of very high impedance and C_5 is a large capacity introduced to reinforce C_3 and C_4 in insulating for direct current; if L_3 and C_5 are made somewhat smaller they will have a qualitative effect in the radio-frequency system, but will not change the essential operation. The circuit of Fig. 5 was the basis of certain models of a successful commercial receiver known as the "Thermodyne".

In order that one skilled in the art may immediately practice this invention, the following constants for the system of Fig. 5 are given:

L_1+L_2 =one tapped solenoid coil of 390 microhenries inductance, tapped so that $L_1=12$ microhenries.

$C_5=1$ to 10 milli-microfarads.

$C_3=2$ to 10 milli-microfarads.

$C_4=$ variable condenser having a range of from 15 to 220 micro-microfarads.

$L_3=$ a choke coil of not less than 500 microhenries inductance.

It will be observed that when values of the order of those given above as applicable to the system of Fig. 5 are assigned to the elements, the mutual reactance of the input and output circuits of the coupling system is fairly low. This result follows from the fact that the inductance of L_1 is small in comparison with that of L_2 , and that the capacity of C_3 is large in comparison with that of C_4 . Since the mutual reactance between the input circuit and the variably tunable absorbing circuit of the coupling system is small, the react-

ance of the tunable absorbing circuit is not reflected into the said input circuit to a sufficient extent to cause the output impedance connected to the amplifier to act through the internal grid-plate capacity of the said amplifier tube and cooperate with the currents in the amplifier input to a sufficient extent to produce oscillation. The tendency toward oscillations in amplifier coupling circuits is particularly pronounced when the input circuit of the amplifier tube is tunable in consonance with the tunable circuit associated with the coupling system in the output of the amplifier tube; such tunable circuits are shown, for example, in Fig. 9.

The objects of this invention may be attained by a great number of circuits, of more or less complexity. For example, one of the simpler embodiments of the invention may comprise a modification of the circuit arrangement of Fig. 2 as by replacing the choke-coil L_3 by a radio-frequency self-inductance and the blocking condenser C_5 by a radio-frequency condenser, the two being designed to be resonant together at a frequency somewhat lower than the lowest frequency of the signals to be amplified. Under these conditions, the voltage ratio E_2/E_1 is no longer substantially independent of the frequency, but falls off at the lower radio frequencies due to the approach to resonance of L_3 and C_5 in parallel, the increase in input impedance thus compensating at least in part for the variation in the coupling reactance provided by the coil L_1 . This arrangement, however, is not so desirable as that of Fig. 4 or Fig. 5; for the voltage ratio will be relatively too high at intermediate frequencies, with the result that the response curve tends to have a dip in the central portion, as illustrated by the dotted curve in Fig. 2A.

In Fig. 6, which illustrates a coupling system in many respects similar to that system illustrated in Fig. 2 of my Patent No. 1,762,431 above referred to, the voltage ratio E_2/E_1 will be substantially constant if the coil L_3 is a choke coil of high impedance. This voltage ratio is obtained from a double step-up, first between C_3 and the combination of C_3 and C_5 , and then between L_1 and L_2 ; but both of these step-up ratios are constant under the condition just stated. The response-frequency curve is then given by the full-line curve of Fig. 2A. However, if L_3 is made a lower radio-frequency self-inductance, so as to be resonant with the combination of C_3 and C_5 at a somewhat lower frequency than that of any signal to be amplified, then a variable voltage will be obtained which will automatically vary with the frequency in the same manner as for Fig. 2 when modified as described in the preceding paragraph. The response-frequency curve is then given by the dotted curve in Fig. 2A. The circuit of Fig. 6, when adjusted in this manner, was employed in some of the earlier models of the mentioned "Thermodyne" receiver.

Fig. 7 shows a modification of Fig. 6, which obtains a voltage ratio which varies automatically with the frequency by the insertion of a small self-inductance L_6 in series with C_3 . L_6 is given such a value that its reactance is lower than that of condenser C_3 at all frequencies to which the system is to respond. At relatively high frequencies it will subtract a relatively large portion of the reactance of C_3 , thus giving a relatively low voltage E_1 between the plate and the filament. This makes the step-up ratio E_2/E_1 increase as the frequency rises, which is the result desired.

5 However, this effect does not become important except near the high-frequency end of the range. The result is that the voltage ratio is relatively 10 too low at intermediate frequencies, and the response curve is correspondingly too high, as illustrated in Fig. 7A. The system is therefore inferior to that of Figs. 4 and 5.

10 Fig. 8 shows a system embodying my invention in which the primary circuit C_5 , L_1 , L_2 is isolated from the secondary circuit C_2 , L_2 . The proportions of C_5 , L_1 and L_2 and the couplings between L_1 , L_2 and L_3 may be adjusted to give a 15 desirable variation with frequency of the voltage ratio E_2/E_1 . This modification of my invention is more fully described in my United States Letters Patent No. 1,763,380, granted June 10, 1930, which is a continuation-in-part of the present application.

20 Fig. 9 shows the application of the arrangement 20 of Fig. 5 to a complete uni-control radio-frequency amplifier, both as coupling between the antenna and the grid of the first vacuum tube and as coupling between consecutive vacuum tubes. The advantages of applying such a compound coupling system to an antenna circuit are: first, to permit of attaining at all frequencies the most suitable compromise between sensitivity and selectivity; and second, to make the electrical constants of the tuned antenna system and 25 the subsequent coupling systems substantially identical at all frequencies, so as to permit them to be tuned alike, particularly when it is desired to employ a single control for tuning all circuits, as has been done in the "Thermiodyne" receiver.

30 35 It is to be understood that by the terms "antenna" and "antenna and ground", as employed in this specification and the appended claims, is meant any suitable system for collecting radio-frequency energy to which the input terminals of 40 an amplifier would customarily be connected.

I claim:

1. An electric coupling system adapted to be interposed between elements of a radio signaling apparatus, including terminals across which an 45 alternating voltage is developed, a main resonant circuit across which an output voltage is developed, and means for adjusting said circuit over a certain frequency range, an input path through 50 said coupling system, and means including said path for causing the ratio of the output voltage to the accompanying alternating voltage in said input path of the coupling system to rise as the frequency of said resonant circuit is increased, whereby high degrees of sensitivity, selectivity and 55 stability are maintained.

2. A tuned radio-frequency coupling system interposed between elements of a vacuum tube radio-frequency amplifier, including terminals across which an alternating voltage is developed, 60 an adjustable main resonant circuit across which an output voltage is developed, an input path through said coupling system, and means including capacity and inductance in said input path for causing the ratio of the output voltage to the 65 accompanying alternating voltage in said path to rise as the frequency is increased, whereby high degrees of sensitivity, selectivity and stability are maintained.

3. In a radio-frequency signaling apparatus including vacuum tubes, an electric coupling system including the combination of fixed reactive elements and a resonant circuit across which an output voltage is developed, said resonant circuit having a single adjustable tuning element, said 70 coupling system being interposed between two

vacuum tubes of said apparatus, said fixed reactive elements being so arranged that between two points thereof there is developed an alternating voltage which automatically falls off relative to said output voltage when said tuning element alone is adjusted for higher frequencies. 5

4. In a radio-frequency vacuum tube amplifier, an electric coupling system including a combination of fixed reactive elements and a resonant circuit across which an output voltage is developed, said resonant circuit having a single adjustable tuning element, said coupling system being interposed between two vacuum tubes of 10 said amplifier, each tube having a grid, a plate and a filament, said output voltage being impressed across the grid and the filament of one of said vacuum tubes, said fixed reactive elements being so related to each other and to said vacuum tubes that between the plate and the filament of the other of said tubes there is developed an 15 alternating voltage which automatically falls off relative to said output voltage when said tuning element alone is adjusted for higher frequencies. 20

5. In a radio amplifier stage, including a vacuum tube having a filament, a grid and a plate, 25 an electric coupling system comprising a main resonant circuit in which a resonant voltage is built up, a path through said coupling system between said plate and said filament, a fixed condenser in series both with said path and with 30 said main resonant circuit, and reactive means so associated with said path and with said main resonant circuit that there is developed in said path a voltage whose ratio to said resonant voltage falls rapidly as the frequency is increased. 35

6. A system of amplification of radiant energy comprising an electronic device, a transformer, a tuning capacity, a capacity connected in series between the primary and secondary of the transformer, said capacity being also in series with the 40 tuning capacity, and both capacities being connected in shunt across the secondary of the transformer, and the electrical values of the said inductances of the transformer and of the said 45 capacities being relatively such that the system is essentially nonregenerative.

7. A system of amplification of radiant energy as set forth in claim 6 which provides capacities to form an electrostatic path of energy transfer whose value is definitely variable, and inductances comprising a transformer to form an electromagnetic path whose value is naturally variable with changes of frequency; the electrical relationship of these two paths and their values being such that a maximum transfer of energy 55 is obtained without regeneration or any flow of undesirable disturbing currents at any desired frequency.

8. A system of amplification of radiant energy as set forth in claim 6 which comprises an electromagnetic and an electrostatic path of energy transfer whose values are variable, automatically, by the act of tuning, said values being so related to each other as to produce a zero difference of potential in respect to all undesired currents between the grid and plate of the electronic device when the set is tuned to any given frequency. 60

9. A system of amplification of radiant energy comprising an electronic device, a transformer, a tuning capacity, a capacity connected in series 70 between the primary and secondary of said transformer, said capacity being also in series with the tuning capacity and both capacities being connected in shunt across the secondary of the transformer, and the electrical values of said 75

5 inductances and capacities being so selected and so related to each other as to simultaneously maintain a condition of complete non-regeneration and a condition of energy transfer maintained constant at its maximum value at any desired frequency.

10. A system of amplification of radiant energy comprising an electronic device having an output circuit which comprises a transformer, a variable 10 condenser, and a series condenser, said variable and series condensers being connected in series with each other and the two being connected in shunt across the secondary of said transformer and one end of the primary of said transformer 15 being connected into the series connection between the two said condensers and their values being selected so as to prevent the production of undesired disturbing oscillations in the electronic device.

20. 11. In a system of amplification of radiant energy comprising an electronic device, a transformer, a tuning capacity, a capacity connected in series between the primary and secondary of said transformer, said capacity being also in series with the tuning capacity, and both capacities being connected in shunt across the secondary of the transformer, the process of simultaneously maintaining a condition of complete non-regeneration and a condition of energy transfer maintained constant at its maximum value over any desired range of frequency by the selection and relation of the electrical values of said inductances and capacities.

12. An electric coupling system for coupling a 35 pair of input terminals to a pair of output terminals, said system comprising an inductive coupling element which acting alone would produce a voltage across said output terminals which rises with increasing frequency, and reactance means 40 included in said system for maintaining said output voltage fairly constant over a substantial range of frequency.

13. An electric coupling system for interposition between a pair of input terminals and a pair 45 of output terminals, said system comprising an exciting circuit and a tunable output circuit coupled to said exciting circuit, said exciting circuit including an element which acting alone would produce a voltage in said output circuit which 50 rises with increasing frequency, and reactive means in said exciting circuit for causing the voltage across said input terminals to decrease with increasing frequency, whereby the voltage across said output terminals remains substantially constant.

55. 14. An electric coupling system having a pair of input terminals and a pair of output terminals, said system comprising an exciting circuit connected to said input terminals and an absorbing 60 circuit connected to said output terminals and coupled to said exciting circuit, said system including only one manually variable element which selects the frequencies transmitted by said system, and said exciting circuit including elements 65 whose impedances vary with frequency in such a manner that the voltage across said input terminals automatically decreases when the tuning frequency is increased, while the output voltage remains substantially constant.

70. 15. An electric coupling system comprising two pairs of terminals, a variable condenser-tuned circuit connected with one of said pairs of terminals and a network including fixed reactance elements connected with the other of said pairs 75 of terminals, at least one of said elements being

coupled to said tuned circuit, and at least two of said elements having different reactance variations with change of frequency, whereby the total effective coupling can be made any desired function of the frequency to which said circuit 5 is tuned.

16. A tuned radio-frequency coupling system comprising two pairs of terminals, a tunable circuit connected with one of said pairs of terminals, and a network including fixed reactance elements 10 connected with the other of said pairs of terminals, at least one of said elements being coupled to said tunable circuit, and at least two of said elements having different reactance variations with change of frequency, the values of said two 15 elements being so proportioned and said elements being so related to said tunable circuit that the total effective coupling is a preselected function of the frequency to which said circuit is tuned.

17. A tuned radio-frequency coupling system 20 comprising two pairs of terminals, a tunable circuit connected with one of said pairs of terminals and a network of fixed reactance elements connected with the other of said pairs of terminals, at least one of said elements being inductively coupled to said tunable circuit, and at least two of said elements having opposite reactance 25 variations with frequency, whereby the effective mutual reactance can be made substantially independent of the frequency to which said circuit 30 is tuned.

18. A tuned radio-frequency coupling system comprising two pairs of terminals, a tunable circuit including a variable condenser and a fixed inductance connected in parallel to one of said 35 pairs of terminals and a network of fixed reactance elements connected with the other of said pairs of terminals, at least one of said elements being coupled to said tuned circuit, and at least two of said elements having different reactance 40 variations with frequency, the values of said two elements being so proportioned and said elements being so related to said tunable circuit that the total effective coupling is a preselected function 45 of the frequency to which said circuit is tuned.

19. A radio-frequency coupling system comprising two pairs of terminals, a tunable circuit including a variable condenser and a fixed inductance connected in parallel to one of said 50 pairs of terminals, and a network of fixed reactance elements connected with the other of said pairs of terminals, at least one of said elements being capacitively coupled to said tunable circuit, and at least two of said elements having opposite reactance variations with frequency, 55 the values of said two elements being so proportioned and said elements being so related to said tunable circuit that the total effective coupling is a preselected function of the frequency to which said circuit is tuned.

20. A tuned radio-frequency coupling system comprising two pairs of terminals, a tunable circuit connected with one of said pairs of terminals, and a network including fixed reactance elements connected with the other of said pairs 60 of terminals, at least one of said elements being coupled to said tunable circuit, and at least two of said elements having different reactance variations with change of frequency, said fixed reactance elements being of such types and having 65 such circuit relationship with each other and with said tunable circuit that the total effective coupling can be made any desired function of the frequency to which said circuit is tuned by properly proportioning the values of said elements. 70 75

21. A tuned radio-frequency coupling system comprising two pairs of terminals, a tunable circuit connected with one of said pairs of terminals, and a reactance network connected to the other of said pairs of terminals and including fixed reactance means coupled to said tunable circuit which acting alone produces a ratio of output voltage to input current which varies in a predetermined manner with the frequency to which said circuit is tuned and fixed reactance means for substantially modifying the manner of variation of the voltage introduced into said tunable circuit by said input current as said circuit is tuned over its range, thereby to modify said ratio of output voltage to input current in a preselected manner. 5
22. A tuned radio-frequency coupling system comprising two pairs of terminals, a tunable circuit connected with one of said pairs of terminals, and a reactance network connected to the other of said pairs of terminals and including fixed reactance means coupled to said tunable circuit which acting alone produces a ratio of output voltage to input current which increases with the frequency to which said circuit is tuned, and means for varying the voltage introduced into said tunable circuit by said input current inversely in accordance with said frequency to which said circuit is tuned, thereby to compensate at least in part for the variations in said ratio. 10
23. An electrical system composed of an amplifier of alternating currents, a tunable input circuit, an output circuit, an internal path in said amplifier connecting said output circuit to said input circuit, a tunable absorbing circuit associated with said output circuit, and means for limiting amplified energy feedback through said internal path comprising means for loosely coupling said absorbing circuit to said output circuit and electrical elements maintaining said coupling constant while said absorbing circuit is tuned in consonance with said input circuit. 15
24. An electrical amplifying system including a three-electrode vacuum tube, an adjustable period circuit connected to the input electrodes of said tube, an output circuit, a responsive device, and means for controlling the reaction of said output circuit and abstraction of energy therefrom for said responsive device over a wide range of frequencies that a predetermined effect in said responsive device with frequency is obtained, including a circuit coupled to said output circuit adapted to be adjusted in period in consonance with said adjustable period input circuit, and across which second adjustable circuit said responsive device is connected, said coupling including a pair of coupling elements transferring energy in phase, one of which couplings increases in effect with frequency increase and the other of which couplings decreases in effect with frequency increase, the relative values of said couplings being chosen to give the said predetermined effect over a wide range of frequencies. 20
25. In an electrical system including a source of alternating currents of a wide range of frequencies, the electrical conduct of said source towards currents of different frequencies depending upon the nature of the reactions to said currents of different frequencies of a circuit connected to the output terminals thereof, the method of controlling said reactions with frequency as the current output of said source is changed from frequency to frequency which consists of selectively absorbing energy both electrostatically and electromagnetically in phase from said output circuit in frequency consonance with the currents therein to selectively create absorption reaction thereon, controlling said selective absorption electrostatically whereby said electromagnetic absorption decreases with frequency decrease, and so relating the variation of electrostatic absorption to the necessary electrostatic variation for selective absorption that said electrostatic absorption increases with frequency decrease at such rate that the effect of said electromagnetic absorption on the reactions of said output circuit with frequency is modified in a desired way. 25
26. In an electrical system including a source of alternating currents of a wide range of frequencies, the electrical conduct of said source towards currents of different frequencies depending upon the nature of the reactions to said currents of different frequencies of a circuit connected to the output terminals thereof, the method of controlling said reactions with frequency as the current output of said source is changed from frequency to frequency which consists of selectively absorbing energy from said output circuit by way of a coupling which transfers energy increasingly with frequency increase in frequency consonance with the currents therein to selectively create absorption reaction thereon, further simultaneously selectively absorbing energy from said output in phase with said first selective absorption by way of a coupling which transfers energy decreasingly with frequency increase, and selecting the rate of change of energy transfer with frequency of one of said couplings to produce a predetermined character with frequency of combined absorption reaction on said output circuit whereby the conduct of said source with frequency is controlled in a desired way. 30
27. In an electrical system the combination of a source of alternating currents of a wide range of frequencies, an output circuit, the electrical conduct of said source towards currents of different frequencies depending upon the nature of the reactions of said output circuit to said currents, and means for controlling the electrical conduct of said source from frequency to frequency through control of said reactions comprising a circuit variable in period over said wide range of frequencies coupled to said output circuit through a coupling which changes the absorption reaction of said variable circuit on said output circuit as varied from frequency to frequency, and a second coupling between said circuits in phase accord with said first coupling, said second coupling being adapted to change the absorption reaction of said variable circuit on said output circuit from frequency to frequency inversely to the change produced by said first coupling. 35
28. The method of transferring electrical energy throughout a range of frequencies from an exciting circuit to a tunable absorbing circuit, which consists of transferring the energy both electromagnetically and electrostatically in aiding phase, and causing said electrostatic energy transfer to decrease as said absorbing circuit is tuned in such sense as to increase the frequency of the energy so selected for transfer in substantially the same degree as the electromagnetic energy transfer increases through such tuning. 40
29. An electrical energy transfer system comprising means for transferring energy throughout a range of frequencies from an exciting circuit to a tunable absorbing circuit including a coupling between said circuits comprising in combination 45

5 a capacitive reactance element and an inductive reactance element poled to transfer energy in aiding phase, the reactions of said elements being adjusted to produce a resultant energy transfer which remains substantially constant with frequency variations as said absorbing circuit is tuned.

10 30. An electrical energy transfer system including an exciting circuit and a tunable absorbing circuit, an electrostatic coupling between said circuits, and an electromagnetic coupling between said circuits, said couplings being so poled and relatively adjusted that, for such adjustment, their combined energy transfer remains 15 substantially constant with frequency as said absorbing circuit is variably tuned.

20 31. The method of transferring electrical energy throughout a range of frequencies from an exciting circuit to a tunable absorbing circuit, which consists of transferring the energy both 25 electromagnetically and electrostatically in aiding phase, and causing said electrostatic transfer to vary in a preselected manner as said absorbing circuit is tuned.

25 32. The method of transferring electrical energy throughout a range of frequencies from an exciting circuit to an absorbing circuit whose constants include a capacitive reactance divided into two portions, which consists of transferring 30 energy in aiding phase both electromagnetically and, through one of said capacitive portions, adjusting said absorbing circuit for resonance with desired current frequencies in said exciting circuit by varying the other of said capacitive portions, and adjusting the relative values of said 35 capacitive portions to produce an energy transfer that combines with the electromagnetic energy transfer to produce a combined transfer that varies in a preselected manner with frequency.

40 33. An electrical energy transfer system including an exciting circuit and a tunable absorbing circuit, an electrostatic coupling between said circuits adapted to decrease in a preselected manner with increase of frequency as said absorbing circuit is tuned, and an electromagnetic coupling between said circuits so poled as to transfer energy in phase with said electrostatic coupling.

45 34. An electrical energy transfer system including an exciting circuit and a tunable absorbing circuit, an electrostatic coupling between said circuits adapted to decrease in a preselected manner with increase of frequency as said absorbing circuit is tuned, an electromagnetic coupling between said circuits so poled as to transfer energy in phase with said electrostatic coupling, and a condenser in said exciting circuit in series with said couplings.

50 35. A tunable radio-frequency coupling system comprising a circuit tunable over a wide range of radio frequencies, another circuit to be coupled

therewith, fixed reactance coupling means including inductance for providing coupling therebetween which varies with frequency in one sense as said tunable circuit is tuned over said range, and fixed reactance coupling means including capacitance for providing coupling therebetween which varies with frequency in the opposite sense, said coupling means being relatively poled in aiding phase, whereby the coupling variation of one said means at least partially compensates for the coupling variation of the other said means.

55 36. A tunable radio-frequency coupling system comprising a resonant circuit including inductive and capacitive elements, only one of said elements being adjustable for tuning said circuit over a wide range of radio frequencies, another circuit to be coupled therewith, fixed reactance coupling means including inductance for providing coupling therebetween which varies 20 with frequency in one sense as said tunable circuit is tuned over said range, and fixed reactance coupling means including capacitance for providing coupling therebetween which varies 25 with frequency in the opposite sense, said coupling means being relatively poled in aiding phase, whereby the coupling variation of one said means at least partially compensates for the coupling variation of the other said means.

30 37. A tunable radio-frequency coupling system comprising a resonant circuit including fixed inductance and adjustable capacitance for tuning over a wide range of radio frequencies, another circuit to be coupled therewith, fixed reactance coupling means including inductance for providing coupling therebetween which increases with increasing frequency as said tunable circuit is tuned over said range, and fixed reactance coupling means including capacitance for providing coupling therebetween which decreases with increasing frequency, said means being relatively poled in aiding phase, whereby the coupling variation of one said means at least partially compensates for the coupling variation of the other said means.

35 38. A tunable radio-frequency coupling system comprising a resonant circuit including in series a fixed inductance element, a fixed capacitance element and an adjustable capacitance element for tuning the circuit over a wide range of radio frequencies, and another circuit including in series said fixed capacitance element and another fixed inductance element inductively coupled with that of said resonant circuit, said inductive coupling being poled to aid the coupling 50 of said fixed capacitance, whereby the variation of coupling due to said fixed capacitance element at least partially compensates for the coupling variation due to said inductive coupling as said resonant circuit is tuned over said range.
